Gottlieb Liebender
Inventor.

UNITED STATES PATENT OFFICE

GOTTLIEB LIEBENDER, OF OLSNITZ, GERMANY, ASSIGNOR TO KOCH & TE KOCK, OF OLSNITZ, GERMANY, A FIRM

CARD-SAVING MOTION

Application filed May 3, 1928, Serial No. 274,781, and in Germany March 18, 1927.

In the present invention the mechanically acting machine parts, which are adjusted by the jacquard device for the purpose of selecting the weft thread to be inserted in the shed, 5 can remain in their adjusted position, if the same adjustment is successively made in the same manner, that is to say, said devices can remain in an adjusted position as long as the repetition of the same adjustment continues. 10 This is achieved by interrupting the forward movement of the jacquard card drive by means of a variable control mechanism comprising a system of feed discs adapted to interrupt the forward movement of the jac- 15 quard card for any length of time.

The invention is illustrated in the accompanying drawings, in which Figure 1 is a front view of the variable control mechanism adapted to move the jacquard card forward 20 step by step; Fig. 2, a side view of the device disclosed in Fig. 1 showing the moment the jacquard card is moved forward; Fig. 3, a side view of the same device but in different position indicating the moment when the 25 periodic movement of the card feed is interrupted; and Fig. 4, a view of a feed disc, several of which, differing as to slotting and toothing, being employed to effect a variable interruption of the movement.

Referring to the drawings, the ratchet wheel 4 is rigidly secured to the shaft 1 (Fig. 1) of the card cylinder 2 for the jacquard card 3, and the teeth of the ratchet wheel 4 mesh with the pawl tooth 5 which swings 30 about the shaft 6 journaled in the bearing boxes 7 (Fig. 1) and adapted to be moved by them forward and backward in the slot guides 8 of the walls 9. The shaft 1 further carries the rotatable feed discs 10^{a-f}, each 35 of which has a different circumferential shape (see Figs. 4 and 2) and can be brought into engagement with a pawl 11 which is attached to a bar 12 arranged parallel to the shaft 1 and adapted to slide longitudinally. 40 The bar 12 slides in a guide 13 kept in position by the arms 14 swinging about the shaft 6. The arms 14 are united by a bolt 15 with the pawl 5 so as to form a rigid unit. To move the bearings 7 forward and backward 45 in the slots 8, a bell crank 17, 18 is pivoted at

16, and the arm 18 of said lever is provided at its upper end with a shiftable fork 19 which surrounds the shaft 6. A working movement of lever 18, 19 will cause the lever 18, 19 to swing about its axis and thereby shift the 55 shaft 6 to the extent indicated by α which is equal to one movement of the feed wheel. The discs 10 are provided with shallow and deep slots 20 and 21 at their circumference.

The lateral shifting of the bar 12, which is 60 necessary to bring the pawl tooth 11 in engagement with the teeth of one of the discs 10^a, takes place by means of a swing lever 22 shifting the bar 12 laterally against the resistance of a tension spring 23 into the position as shown in dotted lines at 12'. In the meantime, one of the detents 26 around the bolt 25 is swung from the jacquard outfit by means of one of the cords 24 into the path of the bar 12 so that the stop 27 must strike one 70 of the detents, for example, the detent 26' if the bar 12 is pulled back by the spring 23. In this way the movement of the bar is interrupted and the pawl tooth 11 is then located above the feed disc intended for it. 75

The device functions as follows:

The forward movement of the feed cylinder 2 can take place only, if the pawl 5 can be brought into engagement with the teeth of the ratchet wheel 4 keyed with the feed cylinder to a common shaft. However, the pawl 5 can mesh with the teeth of the ratchet wheel 4 only, if the tooth of the member 11 can enter one of the deep slots 21 of one of the intermediate feed discs 10, for the position of the pawl 5 relative to that of the member 11 is fixed once for all by the bolt 15 with the result that the pawl 5 cannot get within reach of the teeth of the ratchet wheel 4 unless it goes deep enough down. This greater or lesser lowering of the pawl is regulated by the circumference of the feed discs 10 whose deep slots are spaced in a certain manner insuring perfect timing. During the rest of the time the tooth of the member 11 is raised only slightly and, owing to the shallow slots, adapted to a normal tooth, cannot drop down beyond the tooth depth. 95

As already stated, the tooth 11 is always 100 moved rhythmically in the general direction

indicated by the arrows shown in Fig. 2 as crossing lever arm 18, and if it does not enter one of the deeper slots, its motion simply moves forward the loosely attached discs 10. 5 As soon as the tooth 11 enters one of the deep slots, it naturally can be lowered much more and with it the pawl 5 with the result that the pawl 5 gets within reach of the teeth of the ratchet wheel 4 and the latter is moved one step during the feed motion.

10 The device referred to serves for keeping the hooks, &c., taken in by the jacquard device in their adjusted position as long as the repetition of the same adjustment continues.

15 Having thus described my invention, I claim:

1. In a jacquard card driving mechanism for looms, a card cylinder, a pawl and ratchet wheel drive mechanism for intermittently rotating the same, a series of feed disks loosely rotatable on the card cylinder shaft and provided with notches different in number and depth for variable feed actions, a control pawl engageable with the notches of any of 20 the disks and connected with the drive pawl for shifting the latter into and out of engagement with the teeth of the ratchet wheel, and means for shifting the control pawl relative to the disks for relative engagement with any disk.

2. In a jacquard card driving mechanism for looms, a card cylinder, a pawl and ratchet wheel drive mechanism for intermittently rotating the same, a series of feed disks loosely 25 rotatable on the card cylinder shaft and provided with notches different in number and depth for variable feed actions, a control pawl engageable with the notches of any of the disks and connected with the drive pawl for shifting the latter into and out of engagement with the teeth of the ratchet wheel, a slide for adjusting the control pawl for shifting the same to engage any of the disks, means for variably shifting the slide, and 30 means for actuating the slide and pawls for reciprocating the latter for a feed action.

3. A device according to claim 1 wherein the feed disks are provided with circumferential notches of different depths, the number and grouping of said notches about the circumference of each disk relative to one another being the same on the same disks but differing on different disks to impart different feed values to different disks.

50 In testimony whereof I have affixed my signature.

GOTTLIEB LIEBENDER.
